(57) CLAIM

The ornamental design for an outdoor illuminary assembly, as shown and described.

DESCRIPTION

FIG. 1 is a perspective view of the outdoor illuminary assembly of this invention;

FIG. 2 is a front elevational view thereof;

FIG. 3 is a top plan view thereof;

FIG. 4 is a left side elevational view thereof, the right side being a mirror image;

FIG. 5 is a back elevational view;

FIG. 6 is a bottom plan view;

FIG. 7 is a sectional view taken along line 7—7 in FIG. 1; and,

FIG. 8 is a sectional view taken along line 8—8 in FIG. 3.

The candle member and light bulb assembly are shown in broken lines for illustrative purposes only and form no part of the claimed invention.
